UNITED STATES PATENT OFFICE.

JOHN McE. AMES, OF NEW BRIGHTON, NEW YORK, ASSIGNOR TO BENJAMIN A. HEGEMAN, JR., OF NORTH PLAINFIELD, NEW JERSEY.

DRAFT-RIGGING FOR CARS.

No. 824,698.

Specification of Letters Patent.

Patented July 3, 1906.

Application filed April 12, 1905. Serial No. 255,097.

To all whom it may concern:

Be it known that I, JOHN McE. AMES, a citizen of the United States, and a resident of New Brighton, in the county of Richmond and State of New York, have invented certain new and useful Improvements in Draft-Riggings for Cars, of which the following is a specification.

The invention relates to improvements in draft-riggings for cars; and it consists in the novel features and combinations of parts hereinafter described, and particularly pointed out in the claims.

The object of the invention is to improve draft-riggings employing followers by providing longitudinal bars secured to the sills or timbers and slotting the followers to receive and guide on said bars, said bars in their coöperative action with the followers serving to keep the sills or timbers from spreading under shock.

The invention will be fully understood from the detailed description hereinafter presented, reference being had to the accompanying drawings, in which—

Figure 1 is a vertical longitudinal section through a portion of a car equipped with a draft-rigging embodying my invention, the section being on the dotted line 1 1 of Fig. 2. Fig. 2 is a top view, partly in section, of same; and Fig. 3 is a vertical transverse section of same on the dotted line 3 3 of Fig. 2.

In the drawings, 10 10 designate usual draft sills or timbers or longitudinal parts connected therewith and between which the draft-rigging is supported, and 11 an end sill.

The draw-head 12 has its forward or outer end portion supported as usual and at its inner end is secured by bolts or rivets 14 to the facing ends of the bent bar-yoke 15, as usual, which yoke incloses at their upper and lower sides the followers 16 17, between which are confined suitable draft-springs 18. The yoke 15 at its bend passes across the face 45 of the inner follower 17, as shown.

Upon the facing sides of the sills 10 are bolted the cast plates or frames 19, which correspond with each other, and each of which comprises a base-flange 20, engaging 50 the face of the sill, lateral outwardly-extending flanges 21, which engage upper and lower inner edges of the sill, and lateral inwardly-extending stops or lugs 22. The bolts which

secure the plates or frames 19 to the sills 10 are denoted by the numeral 23.

The followers 16 17 normally respectively engage the stops 22, as shown in Fig. 2, and said followers are at their side portions formed with slots 24 in line with corresponding slots 25, provided in said stops 22.

Upon the inner end bolts 23 are secured the inner ends of the longitudinal parallel bars 26, which extend forwardly through the slots 24 25 in said stops 22 and followers 16 17 and serve as guides for said followers and also as means for preventing the sills from spreading under shock. The slotted followers 16 17, slotted stops 22, and bars 26 constitute the novel features of the present invention, and they are of special importance in that in their coöperative action they keep the sills from spreading under shock, and said bars serve to guide the followers during their customary movements.

I do not confine my invention to any special form of the bars 26, nor in every instance to the means shown for securing and supporting said bars, nor to any special form of the slotted followers 16 17 or stops 22. In every instance, however, the means supporting the bars 26 will be connected with the facing sides of the draft-sills and the slotted followers will connect as well as be capable of sliding on said bars, and hence the construction presented serves to prevent the said sills from spreading, which they would be otherwise liable to do under shock.

What I claim as my invention, and desire to secure by Letters Patent, is—

1. A draft-rigging for cars comprising opposing followers having slots in their opposite side portions, a spring interposed between said followers, and longitudinal guide-bars secured at their ends to the facing sides of the draft-sills of the car and extending through said slots of said followers, whereby said followers and bars are enabled to prevent the spreading of said sills; substantially as set forth.

2. A draft-rigging for cars comprising a draw-head, a yoke secured at its free ends to the upper and lower sides of said draw-head, opposing followers having slots in their opposite side portions, a spring interposed between said followers, and longitudinal guide-bars secured at their ends to the facing sides

of the draft-sills of the car and extending through said slots of said followers, whereby said followers and bars are enabled to prevent the spreading of said sills, said yoke 5 passing above and below said followers and at its inner end engaging the inner follower, while the outer follower is against the inner end of said draw-head; substantially as set forth.

- 10 3. A draft - rigging for cars comprising plates firmly secured to the facing sides of the draft-sills of the car and having slotted stop-lugs extending inwardly therefrom, opposing followers having slots in their side portions 15 in line with the slots in said lugs, a spring in-

terposed between said followers, and longitudinal guide-bars rigidly fastened at one end and thence extending through said slots in said lugs and said followers, whereby said followers and bars are enabled to prevent the 20 spreading of said sills, said stop-lugs serving as stops for said followers; substantially as set forth.

Signed at New York city, in the county of New York and State of New York, this 10th 25 day of April, A. D. 1905.

JOHN McE. AMES.
